Primary Examiner — Karen S Acker

(57) **CLAIM**

The ornamental design for a textile sheet, as shown and described.

DESCRIPTION

FIG. 1 is a top plan view of a single repeat unit of the textile sheet of FIG. 2; and,

FIG. 2 is a top plan view of the textile sheet showing my new design.

The dot dash dot broken line surrounding FIG. 1 indicates the boundary of a single repeat unit of the article and forms no part of the claim design. The dot dash dot broken line surrounding FIG. 2 depicts the boundaries of the claim and forms no part thereof.

1 Claim, 2 Drawing Sheets
